UNITED STATES PATENT OFFICE.

CHARLES W. SCHEDLER, OF MOUNT VERNON, NEW YORK, ASSIGNOR TO
GEO. BORGFELDT & CO., OF NEW YORK, N. Y., A CORPORATION OF NEW
JERSEY.

DESIGN FOR A WATCH-DIAL.

No. 38,677.

Specification for Design.

Patented July 16, 1907.

Application filed June 22, 1907. Serial No. 380,371. Term of patent 14 years.

To all whom it may concern:

Be it known that I, CHARLES W. SCHEDLER, a citizen of the United States, residing at Mount Vernon, in the county of Westchester and State of New York, have invented a new, original, and ornamental Design for a Watch-Dial, of which the following is a specification, reference being had to the accompanying drawing, forming a part thereof,

and which presents a face view of a watch-dial bearing and incorporating my design.

I claim:

The ornamental design for a watch-dial, as shown.

CHARLES W. SCHEDLER.
